CLAIM

The ornamental design for a release key for a security container, as shown and described.

DESCRIPTION

FIG. 1 is a perspective view of a release key for a security container showing my new design;

FIG. 2 is a top plan view thereof;

FIG. 3 is a right side elevational view thereof, the left side being a mirror image;

FIG. 4 is a front elevational view thereof;

FIG. 5 is a rear elevational view thereof; and,

FIG. 6 is a bottom plan view thereof.
